UNITED STATES PATENT OFFICE.

LLOYD M. SEAMAN, OF STONEHARBOR, NEW JERSEY.

CONCRETE CONSTRUCTION.

1,274,946.

Specification of Letters Patent.

Patented Aug. 6, 1918.

Application filed August 2, 1915. Serial No. 43,116.

To all whom it may concern:

Be it known that I, LLOYD M. SEAMAN, a citizen of the United States, and a resident of Stoneharbor, in the county of Cape May, 5 State of New Jersey, have invented certain new and useful Improvements in Concrete Construction, of which the following is a specification, reference being had to the accompanying drawings.

10 My invention relates particularly to the building of structures wherein it is advantageous to employ separately formed sectional units which may be subsequently assembled to form a continuous structure, and 15 is especially directed to the construction of sea-walls, bulkheads, coffer-dams, etc.

The principal objects of my invention are to provide separately formed sectional units, so constructed and arranged that 20 when abutted one with respect to the other, they may be permanently united while extending below the water line, by substantially fluid cement or concrete composition, to form a composite continuous integral structure.

25 Other objects of my invention are, to provide such units with reinforcing lifting members projecting therefrom, which afford convenient ties for the superstructure, which 30 may be in the form of a parapet wall or coping, subsequently formed upon the assembled sectional units; and to provide reinforcing means for locking the adjacent sectional units against relative separation.

35 My invention includes means for drawing the adjacent sectional units together, and also provides means for sealing the joint between the said sectional units while being united.

40 My invention further includes such construction of the sectional units that fluid may be conveniently directed therethrough for the purpose of jetting them into position.

45 My invention comprehends the method of assembling the respective sectional units, particularly as relates to the guiding of said units into position with their adjacent previously positioned companion.

50 My invention also includes all of the various novel features of construction and arrangement of the structure and the method of assembling the composite parts as hereinafter more definitely set forth in detail.

55 In the accompanying drawings, Figure 1 is a fragmentary transverse sectional view

of a bulkhead constructed in accordance with my invention; Fig. 2 is a fragmentary front elevational view of the bulkhead shown in Fig. 1; Fig. 3 is a plan view of 60 the assembled sectional units shown in Figs. 1 and 2; Fig. 4 is a fragmentary front elevational view of the assembled units in Fig. 3, showing the means for guiding them into proper relative alignment; Fig. 5 is a fragmentary plan view, showing the means for drawing the adjacent sectional units together; Fig. 6 is a fragmentary side elevational view of the structure shown in Fig. 5; Fig. 7 is a perspective view of the reinforcing member which serves to lock the adjacent sectional units together; Fig. 8 is a fragmentary perspective view of the spacing frames for the locking members; Fig. 9 is a plan view of modified form of sectional unit; Fig. 10 is a front elevational view of the sectional unit shown in Fig. 9; Fig. 11 is a plan view of another modification of the sectional unit; and Fig. 12 is a front elevational view of the structure 80 shown in Fig. 11.

In said figures, I have illustrated my invention as applied to a sea-wall or bulkhead, which necessarily extends below the water line and which is formed of a series of 85 sectional units 1, which are forced below the water 2 and into the earth 3 by any suitable means, preferably by what is commonly known as the jetting system.

The bulkhead may include a series of piles 90 4, formed of wood or other suitable material, relatively spaced and disposed at a slight distance behind the sectional units 1, and preferably parallel therewith. In order that the bulkhead may withstand the horizontal stresses to which it may be subjected from the land side, it is preferably provided with bracing piles 5, which may be obliquely disposed with respect to the piles 4, and to which said piles 4 and sectional units 1 may 100 be respectively secured by the tie-rods 6 and 7.

The outer end of the tie-rod 7 is provided with an eye 9, which may be extended through the lifting loop 10 in the upper end 105 of the sectional unit 1, as best shown in Fig. 1, and through which eye 9 a retaining key 11 may be extended, as best shown in Fig. 2, to conveniently secure said tie-rod 7 with its respective sectional unit.

As shown in Figs. 1 and 2, the bulkhead may be provided with a parapet wall or cop-

ing 12, which may be superposed upon the sectional units 1 and the piles 4 by molding it thereon in suitably constructed forms, and may extend well below the tops of said units 5 and piles and have the tie-rods 7 embedded therein, as best shown in Fig. 1.

As best shown in Figs. 3 and 4, the sectional units 1 each comprise a slab of concrete of suitable length, breadth and thickness 10 for the conditions which are to be met, having undercut recesses or grooves extending along its lateral edges, which register with similar grooves in its adjacent companions.

15 The grooves of the slabs shown in Fig. 3 are each formed of a cylindrical bore 13, connected with a slot 15 of less width than the diameter of said bore, and opening through the lateral wall 16 of said slabs, so 20 that when the slabs are abutted as shown, they may be integrally united in watertight relation by a key 17 of concrete inserted therein in fluid form and coalesced therewith by setting.

25 The concrete key 17 may be conveniently reinforced to withstand any possible lateral or horizontal strains tending to separate the adjacent slabs or sectional units 1, by alternately forcing the reinforcing locking members 19, shown in Fig. 7, and the lock spacing frames 20, shown in Fig. 8, down into the soft concrete forming the key 17, so as 30 to be embedded therein and protected from the action of moisture when the concrete 35 sets.

As shown in Fig. 7, the locking member 19 comprises the cylindrical ends 22, each having a bore 23 and connected by a relatively thin web 24, and, as shown in Fig. 8, the 40 spacing frame 20 comprises the side bars 25 spaced to axially align with the bores 23 in the locking member 19, and connected by a series of relatively spaced cross-bars 26, all of which tend to strengthen the concrete 45 key 17 and prevent the slabs 1 from being thrust asunder.

It is essential that in sinking the sectional units 1 they be maintained in close relation, and preferably in contact with 50 their adjacent companions, so that their contiguous edges will be abutted when assembled. For this purpose I have provided a guide comprising parallel tubular guiding bars 27, connected at suitable intervals by 55 spacing rods 29, to the upper one of which a suitable lifting loop or bail 30 is attached for the convenient manipulation of said guide.

Said guide is arranged to have one leg or 60 bar 27 disposed in the bore 13 of the last assembled slab, while the other leg or bar 27 serves to guide the next succeeding slab into proper adjacent relation with its companion, as shown at the right side of Fig. 4. 65 This guide may be withdrawn as desired,

and may be conveniently utilized for carrying the fluid concrete to the bottom of the grooves in the slabs.

In some instances, especially where the sectional units 1 are in direct contact with the water while being assembled, it is advantageous to seal the joint between the adjacent units while being united, and, therefore, said units may be provided with plugs 70 32, of wood or other suitable material, to 75 which cleats 33 may be temporarily attached by nails, screws, or other readily detachable means.

As shown in Figs. 3 and 4, the cleats on the adjacent units 1 are complementary to 80 form suitable guides, beneath which the sealing board 35 may be thrust to seal the joint between the adjacent units during the process of filling the grooves with concrete, and while the same is setting.

In Fig. 3 I have shown a transversely disposed abutment 34, formed of concrete slabs 1 and connected with the sea-wall to support it in opposition to the horizontal strains, and may be employed alone for this purpose 90 or may be used in conjunction with the pilings 4 and 5, shown in Fig. 1, as desired.

In some instances there may be a tendency for the slabs 1 to separate when the guide is withdrawn and before the concrete in the 95 grooves has sufficiently set, and for this purpose I provide a wire link 36 having its substantially parallel bars 37 separated to straddle the grooves in the slabs 1, and thereby permit the withdrawal of the guide 100 therefrom. Said link 36 has a bight 38 for engaging the lifting loop 10 of one slab, and a returned bight 39 forming a closed bifurcation which may straddle the loop 10 of the adjacent slab, and which is arranged to receive the wedge 40, which when driven in the direction of the arrow thereon, utilizes the loop 10 of the last mentioned slab to draw said slabs together.

In the form of my invention shown in 110 Figs. 9 and 10, the slab 42 is provided with undercut grooves whose opposite sides 43 and 44 are disposed in outwardly convergent planes. The slab 42 may be provided with suitable passageways 45 and 46 extending 115 longitudinally therethrough, and curving outwardly as they emerge through the bottom of the slab for the purpose of directing fluid therethrough to effect the jetting operation.

In the form of my invention shown in 120 Figs. 11 and 12, the slab 50 is provided with grooves comprising a substantially rectangular bore 52, connected through the lateral wall of said slab by a relatively narrow 125 slot 53.

It is to be understood that suitable reinforcing bars or other reinforcing means may be conveniently included in the concrete structure, and that the lifting loops 10 which 130

serve to connect the slabs with the coping may extend partly through the slab, as shown in Fig. 4, or may extend continuously therethrough, as shown in Fig. 2.

5 My invention is advantageous in that concrete slabs, duly formed, set and hardened, may be assembled below the water line and subsequently integrally united by substantially fluid concrete or cement, and the watertight wall thus formed provided with a coping molded thereon.

I do not desire to limit my invention to the precise details of construction and arrangement herein set forth, as it is obvious 15 that various modifications may be made therein without departing from the essential features of my invention as defined by the appended claims.

Having thus described my invention, I 20 claim:

1. A structure of the class described, comprising sectional units having undercut grooves complementary to the grooves in the adjacent units to form double headed 25 cavities between said adjacent units, means removably coöperative with said grooves for guiding said units into relative parallel alinement, means hardened within said grooves to integrally unite said units, and 30 means comprising a link tending to draw said units together during the hardening of the uniting means.

2. A structure of the class described, comprising sectional units having undercut 35 grooves complementary to the grooves in the adjacent units, to form hollow-headed cavities between said adjacent units, means comprising fluid plastic material poured into said cavities and hardened therein to integrally unite said units, means comprising double-headed keys arranged to be disposed 40 in spaced relation to said plastic material before hardening, and spaced means comprising spaced bars fitted in the hollow of 45 said heads for supporting said keys in spaced relation.

3. A structure of the class described, comprising sectional units arranged to be successively assembled and having undercut 50 grooves which form double headed cavities between adjacent units, means hardened within said cavities for integrally uniting said units, piling embedded in the earth behind the structure formed by said units, a 55 coping formed upon said structure, and tie-rods directly connecting the respective units with said piling, through said coping.

4. A structure of the class described, comprising sectional units arranged to be successively assembled and having undercut 60

grooves which form double headed cavities between adjacent units, means hardened within said cavities for integrally uniting said units, piling embedded in the earth behind the structure formed by said units, a coping formed upon said structure, and tie-rods directly connecting the respective units with said piling and embedded in said coping.

5. A structure of the class described, comprising sectional units forming concrete slabs arranged to be successively assembled and having undercut grooves which form double headed cavities between adjacent units, means coöperative with said grooves 70 arranged to guide said units into relative parallel alinement, means arranged to temporarily seal the joint between said units, means hardened within said cavities for integrally uniting said units, and means arranged to temporarily hold said units together during the hardening process.

6. A structure of the class described, comprising sectional units arranged to be successively assembled and having undercut 75 grooves which form double headed cavities between adjacent units, and provided with recesses disposed at suitable intervals near the edge thereof, plugs disposed in said recesses and cleats temporarily engaged with 80 said plugs and arranged to receive a board or other sealing member for sealing the joint between the respective units during the process of hardening cement inserted in said 85 cavities.

7. A structure of the class described, comprising sectional units having grooves in the lateral walls thereof forming a cavity between said units when assembled, cement introduced into said cavities and hardened 90 therein to unite said units, reinforcing locking members in said cement, and spacing means between said members.

8. In a structure of the class described, means for uniting adjacent slabs of concrete 95 having undercut grooves in their respective adjacent edges, comprising a removable key-device having parallel hollow members substantially conforming in shape to the shape of said undercut grooves and fitting snugly 100 therein, and serving to convey concrete into the cavity formed by the complementary grooves.

In witness whereof, I have hereunto set my hand this 29th day of July, A. D. 1915. 115

LLOYD M. SEAMAN.
